UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

LOCOMOTIVE HEADLIGHT.

Application filed October 27, 1923, Serial No. 671,232. Renewed April 27, 1927.

My invention relates to headlights and particularly to headlights for steam or electric locomotives.

Headlights for locomotive service are subject to adverse conditions such as damage from dust and moisture. The headlights should, therefore, be so made as to be, as nearly as possible independent of such external atmospheric conditions. The effect of dust and moisture on the reflector and the lamp greatly decreases their efficiency. Moisture and dust may also carry material which will cause the reflector to deteriorate or corrode. It is therefore necessary, in devices of this character, to provide a moisture and dust proof closure for the reflector case. One object of my invention is, therefore, to effectively seal the reflector case against dust and moisture.

Another object of my invention is to provide a structure in which the sealing members shall be self-adjusting and shall effectively maintain the seal.

Another object of my invention is to provide a structure which shall be readily accessible for adjustment and removal of the lamp.

Hitherto, devices of this character have been provided with means for excluding dust and moisture which consisted of overlapping flanges. The obvious disadvantage of this structure has been that the joint was not perfectly tight, and did not prevent deterioration of the lighting properties. Such devices have been provided with a door and a lock and a washer between the door and the case, but these had but one point of adjustment. While such a structure provided an adequate closure when new, the wear resulting from the motion of the parts over each other caused the closure to leak on one side. This could only be remedied by replacing the old washer with a new one. In other words, there was only a manual means of adjustment.

My invention is directed to a structure employing resilient washers and a self adjusting closure which prevents leakage of dust and moisture to both the lens and the door joints.

Specifically, the adjusting means is a flange on the door, a resilient sealing gasket between the door and case and a floating hinge. By reason of this arrangement, I effect a tight closure which is constantly

maintained as such even after the parts have been subjected to wear.

Throughout the drawing, constituting a part hereof, and in which like reference characters designate like parts,

Figure 1 is a side elevational view, partially in cross-section, of an assembled reflector case and door;

Fig. 2 is a rear elevational view showing the hinge brackets;

Fig. 3 is a partial side elevational view showing the position of the hinge bolts when the door is open;

Fig. 4 is a cross-sectional view of the hinge bolt;

Fig. 5 is a view showing means for locking the door, and

Fig. 6 is an elevational view thereof.

The headlight consists of a hinged case 1 and the door 2. The door 2 is provided with a lens 3, and is held closed by means of winged nuts 4 and swivel bolts 5. In the door 2 is a channel 6 containing a resilient packing which bears on the outside surface of the lens. The lens is held in place against the packing by means of a clamping ring 7. Nearer the periphery of the door there is another channel 8 containing a resilient packing. The channel 8 opens toward the reflector case and is arranged to receive a flange 9 on the reflector case 1. The door swings on floating hinges which are slidably mounted on brackets or projections 10 on the reflector case. Each of the floating hinges consists of an eye-bolt 11 provided with a stop member or shoulder 12 which rests on the bracket 10 when the door is open, and is moved away from the bracket when the door is closed. On the opposite side of the bracket, the hinge bolt has mounted upon it a helical spring 13 which is maintained in compression between the bracket 10 and the lock nuts 14.

In opening the door, from the position shown in Fig. 4, the hinge bolts are first drawn toward the seats of the brackets 10 by springs 13. This movement is stopped by the engagement of the stops 12 on the hinge bolts with the brackets. From this point, the door is opened in the usual way. In closing, the edge of the door nearest the hinge bolts first comes in contact with the rim of the reflector case, and the flange on the reflector case registers with the groove in the door, thus holding the door in proper

relation to the case. Upon complete closure, the door acts as a lever and draws the hinge bolt through the bracket and the spring is further compressed.

- 5 15 It will be noted that I have provided a structure with a small number of parts which are easily accessible. The door is held in the desired relation to the case, and produces a tight closure by means of the re-
10 silent washers. A floating spring structure also provides an arrangement by which a tight closure is maintained at all times, even after the parts have been subjected to considerable wear.
- 15 Although I have described a specific embodiment of my invention, I do not limit my invention thereto since various modifications thereof will suggest themselves to those skilled in the art without departing from
20 the spirit of my invention, the scope of which is set forth in the annexed claims.

I claim as my invention:

1. The combination with a reflector case, an apertured light-transmitting door and a
25 lock for fastening said door to said case, of a hinge on said door, said hinge comprising retaining members rigidly attached to said door and perforated brackets rigidly attached

to said case, eye-bolts slidably mounted in said brackets, springs mounted on said eye-bolts tending to hold said door and case together, means for confining said springs against said brackets and means in said eye-bolts for limiting the movement of said eye-bolts in said brackets when the door is 30 35 opened.

2. In an illuminating device comprising a reflector case and a light transmitting door, a hinge exterior to said door, a flange on said case and a channel in said door to retain the door in operative relation with said case, resilient means in said channel and a hinge exterior to said door to effect a dust and moisture proof closure of said door, said hinge comprising a perforated bracket 40 45 rigidly mounted on said door, an eye-bolt slidably mounted on said case and hingedly mounted on said bracket, stop means in said eye-bolt to limit the movement thereof, a spring mounted on said bolt to maintain the bolt in tension and means for locking said door in closed relation to said case.

In testimony whereof, I have hereunto subscribed my name this 20th day of October, 1923.

CHRISTIAN AALBORG.
